FOREIGN PATENT DOCUMENTS

CN 307326395 * 5/2022

Primary Examiner — Shannon W Morgan*Assistant Examiner* — Josiah D. Parsons(74) *Attorney, Agent, or Firm* — ScienBiziP, P.C.(57) **CLAIM**

The ornamental design for a tablet, as shown and described.

DESCRIPTION

FIG. 1 is a front, top, left side perspective view of a tablet showing our design.

FIG. 2 is a rear, bottom, right side perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

Broken lines in the drawings, and the regions illustrated with reduced opacity, depict portions of the Tablet which form no part of the claimed design.

1 Claim, 8 Drawing Sheets(56)
